[57] CLAIM

The ornamental design for a liquid dispensing pouch, as shown and described.

DESCRIPTION

FIG. 1 is a perspective view of a liquid dispensing pouch showing our new design;

FIG. 2 is a front elevational view thereof, the rear being a mirror image;

FIG. 3 is a side elevational view thereof, the side opposite being identical to the side shown;

FIG. 4 is a top plan view thereof;

FIG. 5 is a bottom plan view thereof; and

FIG. 6 is a front elevational view of a second modified embodiment, fragmentarily shown for ease of illustration.

FIG. 1.FIG. 2.FIG. 3.FIG. 4.FIG. 6.FIG. 5.
